Primary Examiner — Rosemary K Tarcza

(57) **CLAIM**

The ornamental design for a battery pack as shown and described.

DESCRIPTION

The patent or application file contains at least one drawing executed in color. Copies of this patent or patent application publication with color drawing(s) will be provided by the Office upon request and payment of the necessary fee.

1. Battery pack

2. Battery pack

1.1: Front

1.2: Back

1.3: Left

1.4: Right

1.5: Top

1.6: Bottom

1.7: Perspective

2.1: Front

2.2: Back

2.3: Left

2.4: Right

2.5: Top

2.6: Bottom

2.7: Perspective

The battery pack is used for storing electrical energy. The red colored parts depict portions of the battery pack that form no part of the claimed design.
